UNITED STATES PATENT OFFICE.

THOMAS C. KEELER, OF MOUNT HOLLY, NEW JERSEY.

COMBINED CHILD'S CHAIR, SEESAW, WAGON, AND SWING.

SPECIFICATION forming part of Letters Patent No. 251,601, dated December 27, 1881.

Application filed September 24, 1881. (Model.)

To all whom it may concern:

Be it known that I, THOMAS C. KEELER, of Mount Holly, in the county of Burlington and State of New Jersey, have invented a new 5 and Improved Child's Chair, of which the following is a full, clear, and exact description.

My invention consists of a high or table chair for children, having such construction that it is adapted to be converted into a seesaw, wagon, 10 or swing.

Reference is to be had to the accompanying drawings, forming part of this specification, in which similar letters of reference indicate corresponding parts in all the figures.

15 Figure 1 is a perspective view of my invention as it appears when arranged for a seesaw or wagon. Fig. 2 is a side elevation as it appears when arranged for a table-chair, and Fig. 3 is a similar view as it appears when arranged for a swing.

In the drawings, *a a* represent the front legs of the chair, which are hinged to the forward ends of the bottom side plates, *e e*; and *b b* represent the rear legs, which are rigidly secured to the said side plates. These side plates are preferably made of metal, and are made to extend rearward past the rear legs a sufficient distance to form the journals for the wheels *d d*, and are braced to the legs by the braces *l l*.

25 Between the forward ends of these side pieces is fixed the round *c*, upon which the springs *f f* of the forward legs are placed. The forward legs extend upward past the seat of the chair *C*, and the arms *g g* of the chair are hinged 30 to them by the strong hinges *h h*, which permit the chair to swing out or to and fro from the legs and cause it to always keep right side up without reference to the position of the legs, whether vertical or horizontal. The front legs

40 are provided with the hooked rods *j j*, and the rear legs are provided with staples or eyes *j' j'*, into which the hooked rods are adapted to be placed for holding the legs together, as shown in Fig. 2, for constituting the table-chair.

45 When the device is to be used for a seesaw the rods *j j* are to be disengaged from the said staples or eyes and the rear legs are to be tipped back upon the floor, as shown in Fig. 1, in which position the front legs serve as spring- 50 supports for the child placed in the chair, and when arranged in this manner the device can

be used as a wagon for wheeling the child about, the round *k* at the upper or outer ends of the rear legs, *b b*, serving as the handle.

To adapt the device for children of different 55 sizes when the device is used as a seesaw, the springs *f f* are made adjustable to different tensions by means of the clasps *i i*, which hold the outer ends of the springs, which are adapted to be moved upon the front legs to and from 60 the round *c*, upon which the springs are coiled; and to prevent the springs from throwing the chair too far forward when there is no weight in the chair the side plates, *e e*, are provided with the stops *n*, against which the lower ends 65 of the front legs will come when they reach the vertical position.

In order to adapt the device for use as a swing, I provide the wheels with the small holes *p p*, which are adapted to be placed upon any 70 suitable hooks fixed in a doorway or other convenient place for suspending the device in an inverted position, in which position the chair proper, *C*, will still be right side up for receiving and holding the child, as in Fig. 3. 75

It is obvious that the wheels *d d* might be dispensed with, as the device could be suspended for a swing by other means, and they are not essential to the use of the device as a seesaw; but they are convenient in moving 80 the child and the chair, and when the device is used as a table-chair they serve as a precaution against all danger of the child tipping itself over, as the wheels, as soon as the forward legs rise from the floor, will permit the 85 chair to roll back, causing the forward legs to drop to the floor again. Besides, the wheels are some distance in rear of the rear legs, and thus make a very broad base.

It will be understood that it is not essential 90 that the side plates, *e e*, be flat, as they can be made round, oval, or in any other ornamental form.

Having thus described my invention, I claim as new and desire to secure by Letters Patent— 95

1. The front legs, *a a*, pivoted to the side pieces, *e e*, in combination with the springs *f f* and the hinged seat *C*, substantially as and for the purposes set forth.

2. The rear legs, *b b*, rigidly secured to the 100 side pieces, *e e*, in combination with the pivoted front legs, *a a*, springs *f f*, and the hinged

seat C, substantially as and for the purposes set forth.

3. The side pieces, e e, extending past the rear legs, b b, and carrying the wheels d d, in combination with the said rear legs and the front legs, a a, springs f f, and the hinged seat C, substantially as and for the purposes set forth.

4. The pivoted legs a a, provided with the hooked rods j j, in combination with the legs b b, having the eyes j' j', the legs a a being operated by the springs f f and carrying the hinged seat C, substantially as and for the purposes set forth.

5. The wheels d d, provided with the holes 15 p p, in combination with the rear legs, b b, side pieces, e e, pivoted legs a a, hinged seat C, and springs f f, as and for the purposes set forth.

6. The pivoted legs a a, in combination with the springs f f and the sliding clasps i i, substantially as and for the purposes set forth. 20

THOMAS CLIFFORD KEELER.
